UNITED STATES PATENT OFFICE.

HERMAN WILL, OF CHICAGO, ILLINOIS.

BOTTLE-FILLING MACHINE.

SPECIFICATION forming part of Letters Patent No. 314,280, dated March 24, 1885.

Application filed September 10, 1883. Renewed December 5, 1884. (No model.)

To all whom it may concern:

Be it known that I, HERMAN WILL, a citizen of the United States, residing at Chicago, in the county of Cook and State of Illinois, 5 have invented a new and useful Improvement in Bottle-Filling Machines, of which the following is a specification.

My invention relates to improvements in bottle filling machines in which the bottle is 10 incased or held in a cup, to prevent the hands from being cut should the bottle break from extreme pressure in filling it; and, furthermore, it consists in having the cup automatically oscillate forward and backward on a 15 horizontal axis, to enable the operator to change the bottles in the cup, and also to bring the bottles under the filling-head.

Figure 1 is a front elevation. Fig. 2 is a vertical cross-section taken through the center of 20 the table.

The general table B, standards j, together with the foot-lever C, which overcomes the springs s s and draws down the filling-head c by means of the rods d d, and the cross-bars 25 above and below, are not new in themselves, nor claimed in this invention, except as connected with the cam D and cup m, for moving the cup to and from the filling position through the action of the foot-lever by moving the 30 pin f.

It will be seen by the curved slot which constitutes the cam D that at the extreme ends of the vertical movements the pin f does not actuate the cam sidewise at all. The hand-lever 35 a is used to raise and lower the rod b, which hooks onto and draws up an internal stopper of the bottle h within the safety screen-cup l m. Underneath the table represented by o is a double metallic bracket to hold the horizontal 40 pin e, about which the cam-lever D oscillates, the bracket o also holding the pins i on both sides of the cam-lever D to limit its motion, while the pin n is to be used in disconnecting

the bottle-cup l m while it is emptied of any broken glass, &c. The stirrup p, which holds 45 the pin f, is rigidly fastened to the lower cross-bar, r, and always moving in conjunction with the rods d d, the cam moving only as the pin passes the central portion of it, at which time it is necessary to throw the bottle from its 50 vertical position, as the filling-head is then sufficiently raised to allow the projecting stopper to pass from under it and off of the hook. The cup m is made of perforated metal, and is also removable, so the broken glass may be 55 easily thrown out and the cup readily replaced. It is sometimes necessary to have the cup and bottle oscillate to the left or back side of the frame, so as to have the bottles taken out and replaced by an assistant to the 60 operator. In such case it is accomplished by removing the pins e and f, taking the cam D out, and reversing it, thereby causing the bottle to oscillate in the reverse direction.

The operation is to place the bottle in its 65 cup; then the operator by the foot-lever causes both the pins f and the filling-head c to come down simultaneously. The pin f throws the bottle-cup immediately to a vertical position, which is the proper one for filling. After the 70 filling-head has been brought down, the bottle is filled; then the stopper is drawn up, the filling-head raised, and the bottle is thrown to one side, as shown in Fig. 2, for a change of bottles.

75

I claim—
In a bottle-filling machine, the combination of bracket o, cam-slotted lever D, pivoted therein and having a detachable safety-screen, l m, and stirrup p, having pin f, as and for the 80 purpose set forth.

HERMAN WILL.
